ANGULAR HEAD FLASHLIGHT CASING, INCLUDING A READILY ATTACHABLE LAMP CONTACT MEANS

Joseph A. Gits, Chicago, Ill., assignor of one-half
to Jules P. Gits, Chicago, Ill.

Application August 29, 1946, Serial No. 693,737

6 Claims. (Cl. 240—10.67)

1

This invention relates to flashlights and more particularly to flashlight casings having heads extending angularly from the barrel and to contact structure therefor.

Flashlights usually comprise a barrel adapted to contain a source of energy, such as a battery, and a head adapted to contain a bulb and reflector assembly. When the head is angularly formed with respect to the barrel, a bridging member is provided at the juncture of the parts to form an abutment for the batteries and also to form a support for a resilient contact completing an electrical circuit from the batteries to the flashlight bulb. The resilient contact is usually attached to the bridging member by means of a rivet extending through the contact member and the bridging member, the riveting being done of course after the flashlight casing is formed. In these instances the rivet also forms the contact on the opposite side of the partition against which the batteries abutted.

To complete these flashlight casings, tools capable of holding the resilient contact and the rivet in place, together with means for riveting, which operated through the angular head as well as through the barrel, had to be provided. Such a manufacturing step is difficult to carry out as well as expensive. Riveting over one end of the rivet requires a considerable force to be exerted which sometimes causes the bridging member to be split. But the inconvenient location of the partition between the angular head and the barrel makes it difficult always to assure that the rivet is properly set before the tools are operated with the result that the contact member is quite often riveted upon the partition in a tilted or canted position. The operation is difficult, and, even with the care of a skillful workman, rejects will exist. The operation is moreover slow and has been found to be quite costly.

It is an object of the invention to provide an improved type of contact structure which eliminates the necessity of the riveting operation heretofore used and provides a novel form of attachment completely eliminating the difficulties experienced when the riveting operation is employed.

It is a further object of the invention to provide a contact structure that may be applied to the flashlight casing without splitting the bridging or partition member or a mounting of the contact member in a tilted or canted position.

In carrying out the invention in one form, a flashlight is provided comprising a barrel adapted to contain a source of energy, and an angular

2

head extending from the barrel adapted to contain a bulb and reflector. A bridging member is arranged between the head and the barrel, and a resilient contact member is supported on the bridging member for contacting the bulb, the contact member including a reversely bent portion that is so formed that mounting of the contact member may be accomplished by merely sliding the same in embracing relation upon the bridging member at one edge and effect an interlocking engagement holding the contact member tightly in erect position to complete the circuit from one to the other side of the bridging member.

For a more complete understanding of the invention, reference should be had to the accompanying drawing, in which:

Fig. 1 is a sectional elevational view of a flashlight casing embodying the invention;

Fig. 2 is a sectional view taken substantially along lines 2—2 of Fig. 1;

Fig. 3 is a sectional view taken substantially along lines 3—3 of Fig. 1;

Fig. 4 is a view on a larger scale of a flashlight contact member embodied in the invention; and

Fig. 5 is an elevational view on a reduced scale of the flashlight casing shown in Fig. 1.

Referring to the drawing, the invention is shown embodied in a flashlight including a barrel 10 and a head 11 extending at right angles thereto, the barrel being of a sufficient diameter and length to receive one or more flashlight batteries 12 (shown in dot-and-dash lines). At the outer end of barrel 10 a circumferential flange 13 is provided against which a closing cap 14 abuts through a sealing gasket 15, the cap 14 and the portion of the barrel beyond flange 13 being threadable to each other. Cap 14 is hollow inside and includes a portion 16 of decreased diameter, thereby forming an internal shoulder 17 against which the base of the spiral contact spring 18 abuts. Within portion 16 a U-shaped bracket 19 is received, the bracket including a pair of spring arms 21 for holding a spare bulb 22.

The angular head 11 may be of any desired shape, but preferably is semi-cylindrical in its over-all contour, and includes a threaded portion 23 extending outwardly from barrel 10. Within head 11 and its portion 23, a bulb 24 and a reflector 25 in a unitary assembly are held by means of a cap 26 having threads corresponding to those of portion 23. A flange member 27 on cap 26 overlies the periphery of a lens 28, the lens bearing against a gasket 29 on one side of

the reflector rim, which in turn bears against a gasket 31 on the other side of the reflector rim to force gasket 31 against the outward edge of portion 23. By screwing cap 26 tightly onto portion 23, the gaskets 29 and 31 are sufficiently compressed to provide a watertight seal at this point in the flashlight casing.

The reflector 25 may be formed of any metal, such as brass, for example, which has been suitably plated with nickel or chromium, for example, to provide an internal reflecting surface, and has a threaded ferrule 32 projecting rearwardly therefrom, the ferrule including an internal shoulder against which a rim 33 attached to the bulb 24 may bear. A hollow plug 34 is threaded into ferrule 32 to bear against rim 33 for holding bulb 24 in its proper position in the reflector and to permit the contact 35 on the bulb to project outwardly from the rear thereof.

Internally of barrel 10 and head 11 are a pair of ribs 36 defining a channel between them, within which channel contact strips 37 and 38 may lie. The ribs 36 extend away from the inside surface of the barrel a sufficient distance so that the channel has enough depth for contact strips 37 and 38 at all times to be out of contact with the outer surface of the flashlight batteries. The rear contact strip 38 is held to the casing at its forward end by means of a rivet 39, and to the casing at its rearward end by a rivet 41 which also connects the contact strip to an annular ring 42 having an outwardly bent flange 43. When cap 14 is screwed onto the flashlight barrel, the internal shoulder 17 causes the base of spring 18 to contact the flange 43.

The forward contact strip 37 is attached at its rearward end to barrel 10 by means of a rivet 44, and includes an angularly-bent portion 45 extending into head 11 and outwardly toward the cap 26, the portion 45 being adapted to contact the outer surface of reflector 25. Resilient portion 45 is formed to be spaced away from the wall of portion 23 so that when the reflector 15, which preferably is arcuate in form, is placed into portion 23, the resilient member 45 is caused to be bent outwardly, thereby rubbing against the surface of the reflector and producing good contact therewith. In order to hold resilient member 45 in its proper position while it is being bent outwardly by the reflector, the lower of the ribs 36 is provided with an upwardly extending projection 46 which prevents contact strip 37 from moving out of the channel formed by the ribs 36.

Contact strips 37 and 38 form part of the electrical circuit within the flashlight casing, and have their adjacent ends spaced apart from each other so as to provide an incomplete circuit. Externally of barrel 10 there is a switch housing 47 attached thereto by means of suitable rivets, and including a thumbpiece 48 which is movable to one or more positions along casing 47. Also arranged in casing 47 is a depressible button 49. The rivet 44 at the rear end of contact strip 37 and the rivet 51 at the forward end of rear contact strip 38 project into the inside of casing 47 and are adapted to complete a circuit between contact strips 37 and 38 through proper manipulation of the thumbpiece 48 and push button 49, as is well understood in this art. One form of contact structure is described in the co-pending application Serial No. 518,942, filed January 20, 1944, entitled Flashlight, to Joseph A. Gits and Jules P. Gits, which application issued October 1, 1946 as Patent No. 2,408,393.

Spaced between angular head 11 and barrel 10, and integrally formed therewith, is a transverse bridging member 52 forming an abutment for the forward end of batteries 12 and forming a support for a resilient contact structure 58. At the lower end of the bridging member, reinforcing wings 53 extend from each side thereof and join the bridging member to the walls of head 11. Similarly, at the upper end thereof there are a pair of wings 54 joining the bridging member to and forming part of the inner walls of head 11. The adjacent edges of reinforcing members 53 and 54 are spaced apart, as is seen best in Fig. 1, thereby forming a space through which the contact strip 37 passes. On the side of bridging member 52 facing the inside of barrel 10 substantially centrally thereof, there is a depression 55, and on the other side thereof there are a pair of ribs 56 projecting into head 11 and spaced apart to effect a channel or guide. At the end of the bridging member adjacent the junction of portion 23 with barrel 10, there is an opening 57 of approximately the same width as the space between ribs 56.

The resilient contact structure 58 completes an electrical circuit between batteries 12 within barrel 10 and the contact point 35 of bulb 24. Referring more particularly to Fig. 4, contact structure 58 comprises a pair of members 59 and 61 lying alongside and spaced from each other, and extending from portion 61 is a curved portion 62 terminating in a relatively flat end 63. The contact structure may be formed from a single blank of flat strip material, and portions 59 and 61 are bent so that portion 59 tends to spring toward the normal free position (shown dotted), and the curved portion 62 causes the flat end 63 to be resilient or springy relative to portion 61. Approaching the outer end of portion 59 there is a protuberance 64 projecting toward portion 61.

Contact structure 58 is attached to the casing by slipping the portions 59 and 61 over the bridging member 52, with portion 59 being forced outwardly and lying on the barrel side of the bridging member and with protuberance 64 being received within depression 55 (Fig. 1). The connecting metallic portion between portions 59 and 61 lies within the opening 57, which opening also permits the contact structure to be slipped onto the bridging member. In the attaching process, the portions 59 and 61 are forced apart, and due to their relative resilience these two members lie tightly against the respective sides of the bridging member, thereby bringing the flat end 63 into position to contact the portion 35 of the bulb 24, as may be seen best in Fig. 1. The curved portion 62 causes the flat end 63 to be resiliently exerted against contact 35. The ribs 56 are spaced apart just a sufficient distance to easily receive the portion 61 of the contact structure between them, and thereby prevent rotation thereof during the use of the flashlight. The protuberance 64 being received within depression 55 prevents removal of the contact structure unless it is desired to do so, at which instant this may be accomplished by exerting considerable force against the end 63 and the curved portion 62, such as by inserting one's finger into the head 11. The relative lengths of portions 59 and 61 form a long bearing surface, so that the force exerted by contact 35 against flat portion 63 does not cause the contact to become loose, the portion 59 being adapted to contact the forward end of batteries within barrel 10.

When the flashlight is completely assembled, as shown in Fig. 1, and the push button 49 and the thumbpiece 48 are manipulated as described in the aforementioned patent application, a complete circuit to bulb 24 is provided through contact 35, contact structure 58, the batteries in the flashlight housing, spring 18, annular ring 42, contact strip 38, the switch members in the housing 47, contact strip 37, the resilient member thereof 45, and through the reflector 25 to the 10 rim 33 of the bulb.

It is preferred that the flashlight, including the casing 10, the head 11, and the bridging member 52, together with its reinforcing members, be formed by molding, say by the injection method, in which all of the various parts are formed integrally with each other. The exterior of barrel 10 and of cap 14 may be provided with ribs 65 and 66, as shown best in Fig. 5, whereby good gripping of these members may be had. Attached to the rear portion of head 11 by rivets, as shown, is a spring hanger 67.

With the contact structure 58 as described, the flashlight casing proper may first be completely formed and the contact structure thereafter manually applied thereto by a simple manual operation, thereby preventing any damage to the bridging member 52 as well as preventing improper positioning of contact structure 58 arising out of the manufacturing process.

Without further elaboration, the foregoing will so fully explain the gist of my invention that others may, by applying current knowledge, readily adapt the same for use under varying conditions of service without eliminating certain features which may properly be said to constitute the essential items of novelty involved, which items are intended to be defined and secured to me by the following claims.

I claim:

1. A flashlight casing comprising a hollow barrel, a hollow head mounted on one end of said barrel and having an angularly disposed open end portion, an end closure mounted on the other end of said barrel, an apertured bridging member transversely mounted within said barrel at substantially the juncture of said barrel and head and forming an energizing source receiving compartment within said barrel and a bulb-reflector receiving compartment within said head, said barrel, head, and bridging member being of an insulating material, the aperture in said bridging member being aligned with and adjacent to the open end portion of said head, and a removable contact piece of conducting material comprising a resilient U-shaped portion having a base and two legs and a resilient bulb contacting portion extending from one of said legs, said base being disposed in said aperture and said legs being tensioned to resiliently engage said bridging member, said bulb contacting portion being disposed within said bulb-reflector-receiving compartment and the other of said legs being disposed in the energizing source-receiving compartment to form an energizing source contact member.

2. A flashlight casing comprising a hollow barrel, a hollow head mounted on said barrel and having an angularly disposed open end portion, an apertured bridging member transversely mounted within said barrel at substantially the juncture of said barrel and head and forming an energizing source receiving compartment within said barrel and a bulb-reflector receiving compartment within said head, said barrel, head, and

bridging member being of an insulating material, the aperture in said bridging member being adjacent to and aligned with the open end portion of said head, and a removable U-shaped bridging member-straddling conducting contact piece having a base portion disposed in said aperture and a leg member disposed on each side of said bridging member and depending from said base portion, the first of said leg members comprising an energizing source-engaging section inserted through said aperture and resiliently engaging the side of said bridging member adjacent said energizing source receiving compartment and the second of said leg members having a first portion resiliently engaging the side of said bridging member adjacent said bulb-reflector receiving compartment and a bulb-contacting portion angularly disposed with respect to said first portion.

3. A flashlight casing comprising a hollow barrel, a hollow head mounted on said barrel and having an angularly disposed open end portion, an apertured bridging member transversely mounted within said barrel at substantially the juncture of said barrel and head and forming an energizing source receiving compartment within said barrel and a bulb-reflector receiving compartment within said head, the aperture in said bridging member being adjacent to and aligned with the open end portion of said head, and a resilient removable conducting contact piece having a base portion disposed in said aperture and a leg member disposed on each side of said bridging member and depending from said base portion, said leg members embracingly engaging said bridging member, the first of said leg members comprising an energizing source engaging leg section inserted through said aperture and slidably engaging the side of said bridging member adjacent said energizing source receiving compartment and the second of said leg members slidably engaging the side of said bridging member adjacent said bulb-reflector receiving compartment and terminating in a bulb-engaging contact.

4. A flashlight casing comprising a hollow barrel, a hollow head mounted on said barrel and having an angularly disposed open end portion, an apertured bridging member transversely mounted within said barrel at substantially the juncture of said barrel and head and forming an energizing source receiving compartment within said barrel and a bulb-reflector receiving compartment within said head, said barrel, head, and bridging member of an insulating material, the aperture in said member being adjacent to and aligned with the open end portion of said head, a resilient removable conducting contact piece having a base portion disposed in said aperture and a leg member disposed on each side of said bridging member and depending from said base portion, said leg member engaging said bridging member, and a contact piece-engaging guide means mounted on said bridging member; the first of said leg sections comprising an energizing source engaging leg section inserted through said aperture and slidably engaging the side of said bridging member adjacent said energizing source receiving compartment and the second of said leg sections retained in said guide means and slidably engaging the side of said bridging member adjacent said bulb-reflector receiving compartment and terminating in a resilient bulb-engaging contact.

5. A flashlight casing comprising a hollow barrel, a hollow head mounted on said barrel and having an angularly disposed open end portion, an apertured bridging member transversely mounted within said barrel at substantially the juncture of said barrel and head and forming an energizing source receiving compartment within said barrel and a bulb-reflector receiving compartment within said head, said bridging member having the side thereof adjacent said energizing source receiving compartment provided with a recessed portion, and a removable contact piece having a base portion disposed in said aperture and a leg member disposed on each side of said bridging member and depending from said base portion, said leg members resiliently embracing said bridging member; the first of said leg members comprising an energizing source engaging leg section inserted through said aperture and slidably engaging the side of said bridging member adjacent said energizing source receiving compartment, said leg section having an offset portion seated in said recessed portion, and the second of said leg members angularly disposed and integrally connected to said first leg section by said base and slidably engaging the side of said bridging member adjacent said bulb-reflector receiving compartment, said second leg member having a protruding bulb-contacting portion disposed within said bulb-reflector receiving compartment.

6. A flashlight casing comprising a hollow barrel, a hollow head mounted on said barrel and having an angularly disposed open end portion, an apertured bridging member transversely mounted within said barrel at substantially the

5

10

15

20
